MAGAZINE TYPE PENCIL

John D. Rossier, Orange, Calif.

Application August 20, 1940, Serial No. 353,353

4 Claims. (Cl. 120—17)

This invention pertains to a magazine-type pencil of novel construction in which the lead is positively and automatically advanced and ejected from the pencil by electromagnetic means.

Magazine-type pencils of various kinds have been manufactured heretofore but all of them include mechanical means for advancing the lead from a lead magazine. Such mechanical means in most instances involve a large number of small parts requiring precise workmanship and are subject to numerous objections. The pencil of this invention, however, is extremely simple in construction and distinguishes from prior pencils in that the lead-advancing mechanism is electrically actuated, the current being derived from a battery carried by the pencil. The electromagnetic lead-actuating means is energized by pressure of a suitable contact switch carried by the pencil and by suitably positioning the switch on the casing of the pencil, the lead may be caused to advance without the necessity of shifting the position of the pencil in the hand, nor does it require the use of two hands, whereas this is generally the case with mechanically operated pencils of this general character.

In accordance with the present invention, the pencil is provided with a removable end portion containing a small battery. The body portion of the pencil includes an electromagnetic coil having a movable armature member carrying lead-gripping means. A suitable switch carried by the casing closes a circuit to the electromagnetic coils, causing the armature to move towards the end of the pencil and thereby advancing the lead a predetermined distance. Repeated closure of the circuit switch will cause repeated advance of the pencil.

An object of the present invention, therefore, is to disclose and provide a magazine-type pencil containing electromagnetic lead-advancing means.

A further object is to disclose and provide a simple and effective construction for a magazine-type pencil in which the lead is advanced electromagnetically.

A further object is to provide a mechanical-type pencil operated by electromagnetic means in which the clip acts as a contact switch.

These and other objects will become apparent to those skilled in the art from the following description of an exemplary form of the invention illustrated in the appended drawing, in which:

Fig. 1 is a longitudinal section through a pencil made in accordance with this invention.

Fig. 2 is a transverse section taken along the plane II—II of Fig. 1.

Fig. 3 is another transverse section taken along the plane III—III of Fig. 1.

Fig. 4 is a longitudinal section of a modified form of advancing means.

Fig. 5 is an enlarged transverse section taken along the plane V—V of Fig. 4.

As shown in Fig. 1, the pencil may comprise a body portion or casing 10 having a conical end portion 11 forming the point of the pencil, a suitably axially directed bore being formed therein and adapted to receive and guidingly support the lead. The opposing end of the casing 10 may be open and may have formed therein threads 12 adapted to engage an internally threaded removable end portion 13. The casing 10 and end portion 13 may be made of any suitable plastic, thermoplastic or thermosetting material, resinous compound, or the like. These parts may also be made of metal but the structure would have to be changed somewhat for reasons which will be apparent hereinafter.

Adjacent the removable end portion 13 and within the casing 10 is a magazine for leads, such magazine being generally indicated at 15. The magazine may be provided with a removable closure 16 carrying a contact point 17. The other end of the magazine may be provided with a port 18 surrounded by inclined end walls 19 leading to said port.

Between the lead magazine 15 and the conical end portion 11 there is positioned an electromagnetic lead-advancing unit; such unit may include a spool 20 provided with a suitable winding of insulated wire 21 and a central bore 22. Slidably positioned within the bore 22 is a movable iron core or armature 23 having a disc-shaped end portion facing the magazine 15. A bore 24 extends through this armature 23, said bore 24 being in alignment with the port 18 from the magazine and in alignment with the end of the pencil. Carried by the outwardly flaring end portion of the armature 23 are two or more lead-gripping means which may comprise resilient members 26 attached by one end to armature 23, the free or movable ends of such members 26 being directed inwardly and toward the bore 24 of the armature 23. The inner edges of the members 26 should be spaced a distance slightly smaller than the diameter of the leads emitted by the port 18.

Between the spool 20 and the outwardly flaring end portion of armature 23 a light spring 27 may be positioned, such spring normally urging the armature 23 out of the bore 22 of the spool 20. The opposite end of the spool 20 may be provided with lead-gripping means which, in the illustrative form, comprise resilient portions 28 inclined toward the axis of the spool 20 and shoes 29 substantially parallel to the axis of the spool 20. The inner edges of the shoes 29 may be slightly roughened, serrated, knurled or the like.

for the purpose of firmly gripping lead fed thereto by the rest of the device.

The device also includes an electrical circuit comprising a battery 30 contained within the removable end portion 13. The battery 30 may be provided with a central terminal 31 adapted to contact the contact point 17. A light spring 32 held between the battery 30 and the end of the removable portion 13 may assure proper connection between the contacts 17 and 31. The contact 17 is connected by means of a flexible wire indicated at 33, with one end of the coil 21 carried upon the spool 20. The other end of the coil may be connected as by a wire 34 to a metallic insert 35 carried by the casing 10. A resilient clip 37 may be attached to the removable end portion 13 by suitable rivet or other metallic element, such element also retaining a flat leaf spring 38 within the end portion 13, such leaf spring 38 being adapted to contact the outer metallic housing of the battery 30, such outer housing forming the other terminal or pole of the battery 30.

From the description given hereinabove, it will be noted that in the event a suitable supply of leads is placed in the magazine 15 and one of the leads extends through the port 18 into the space between the lead-gripping means 26, such lead can be positively advanced toward the end of the pencil by simply pressing the clip 37 against the contact or insert 35. Every time the circuit is thus closed, the coil 21 is energized and the movable lead-advancing armature 23 will move toward the conical end portion 11 of the pencil, returning to its original position under the influence of the spring 27 as soon as the circuit is broken by the resilient clip 37. When used in an ordinary manner, the leads from the magazine 15 will follow each other through the port 18 and may be caused to be ejected or advanced a short distance by simply pressing the spring clip 37 against the side of the pencil. Attention is called to the fact that the lead-advancing means 26 may be said to be uni-directional since the incline of these members toward the bore 24 permits ready entry of lead between the members 26, but the edges of such members resist any backward movement of the lead into the magazine 15. Similarly, the lead-gripping members 28 and 29 may be said to be unidirectional in their effect inasmuch as they resist the return of lead into the pencil and therefore permit any desired writing pressure to be used.

The construction described hereinabove has been referred to as one in which the casing 10 is made of an insulating material. Obviously, metal can be used for the casing of the pencil when desired but in such event the battery needs to be insulated from the removable housing 13 and from the casing 10 except at the terminal 31 and at a point connected with the clip 37, the clip 37 being similarly insulated from the removable end portion 13.

Attention is further called to the fact that ordinarily the end of the clip 37 is spaced from the casing 10 and therefore the circuit is broken. The circuit is also automatically broken when the pencil is carried in the pocket since the clip 37 is then spaced from the casing 10 by the cloth of the pocket.

As shown in the modified form, the electromagnetic advancing means may comprise a spool 43 provided with a coil 21' and a movable armature member 40 provided with the lead-gripping elements 26', the member 40 being movable to-

ward and away from the spool 43 upon pins 42 carried by the end of the spool 43, such pins extending through indentations formed in the edges of the member 40. A very light spirally wound helical spring may be position between the member 40 and the spool 43 for the purpose of moving the member 40 back to its original position at the end of each coil-energizing period.

In this connection, it may be noted that the spring 27 shown in the first embodiment is also spirally wound so that it may compress into a substantially flat thin layer.

I claim:

1. A magazine-type pencil provided with a hollow casing having a conical end portion and an opposite removable end portion; a magazine for leads in the casing adjacent said removable end portion, said magazine being provided with a lead discharge port; an electromagnetic lead-advancing unit in said casing between said magazine and conical end portion, said unit including a movable member provided with lead-gripping means; a battery in said removable end portion, and an electrical circuit connecting said battery and said lead-advancing unit, said circuit including a normally open switch.

2. A magazine-type pencil provided with a hollow casing having a conical end portion and an opposite removable end portion; a magazine for leads in the casing adjacent said removable end portion, said magazine being provided with a lead discharge port; an electromagnetic lead-advancing unit in said casing between said magazine and conical end portion, said unit including a movable member provided with lead-gripping means; a battery in said removable end portion, and an electrical circuit connecting said battery and said lead-advancing unit, said circuit including a normally open switch, said switch comprising a clip carried by said removable end portion.

3. A magazine-type pencil provided with a hollow casing having a conical end portion and an opposite removable end portion; a magazine for leads in the casing adjacent said removable end portion, said magazine being provided with a removable cover plate and a lead discharge port, inclined end walls in said magazine leading to said port, an electromagnetic lead-advancing unit in said casing between said magazine and conical end portion, said unit including a movable member provided with lead-gripping means; a battery in said removable end portion, and an electrical circuit connecting said battery and said lead-advancing unit, said circuit including a normally open switch.

4. A magazine-type pencil provided with a hollow casing having a conical end portion and an opposite removable end portion; a magazine for leads in the casing adjacent said removable end portion, said magazine being provided with a removable cover plate and a lead discharge port, inclined end walls in said magazine leading to said port, an electromagnetic lead-advancing unit in said casing between said magazine and conical end portion, said unit including a movable member provided with lead-gripping means, a spring urging said gripping means toward said magazine; a battery in said removable end portion, and an electrical circuit connecting said battery and said lead-advancing unit, said circuit including a normally open switch.
